UNITED STATES PATENT OFFICE.

WILLIAM O. HORN, OF NEW YORK, N. Y.

DESIGN FOR A COLLAR AND NECKTIE.

SPECIFICATION forming part of Design No. 32,241, dated February 13, 1900.

Application filed December 23, 1899. Serial No. 741,481. Term of patent 3½ years.

To all whom it may concern:

Be it known that I, WILLIAM O. HORN, a citizen of the United States, residing in the city, county, and State of New York, have invented and produced a new and original Design for a Collar and Necktie, of which the following is a specification, reference being had to the accompanying drawing, forming part thereof.

10 The leading feature of my design for a collar and a necktie is a high turn-down collar open at the rear and having its exterior fold composed of separate oblong pieces and its neckband of a single oblong piece and sections of a tie continuous of the rear collar.

The figure represents a front view of a collar and a necktie embodying my design.

In the drawing, A designates a high turn-down collar, and B designates a necktie.

20 The collar A is open at the rear and consists of an outer fold and a neckband, the outer fold being composed of the oblong pieces C C, which are separate in front, as at A'. The tie is composed of sections C' of a tie which are continuities of the rear ends D 25 of the collar.

E designates a loop at the rear of the collar.

Having thus described my invention, what I claim as new, and desire to secure by Letters Patent, is—

30 The design for a collar and necktie substantially as shown and described.

WILLIAM O. HORN.
